PNEUMATIC BELLOWS

Donald C. Turner, Penfield, N. Y.

Application May 17, 1954, Serial No. 430,100

6 Claims. (Cl. 230—165)

This invention relates to a self-expanding hand bellows having an accordian pleated bellows section and provided with internal air directing means.

An object of the invention is to provide a mere satisfactory and generally improved hand bellows. Another object is to provide a self-expanding hand bellows having an accordian pleated bellows section.

Still another object is to provide a bellows having internal air directing means which also serve air intake means during alternate expansion and contractions of the bellows section.

A further object is the provision of flexible stop means which limit the expansion of the bellows and which function to lock the bellows in contracted position when not in use.

A still further object is to provide a hand bellows which is of simple construction, can be easily and economically fabricated, and requires little or no instruction in use.

These and other desirable objects may be attained in the manner disclosed as an illustrative embodiment of the invention in the following description and in the accompanying drawings forming a part hereof, in which:

Fig. 1 is a front elevation of the hand bellows;

Fig. 2 is a right side elevation of the bellows shown in Fig. 1, with a portion thereof being broken away;

Fig. 3 is a view similar to Fig. 2 showing the bellows in expanded position;

Fig. 4 is a view similar to Fig. 1 with the front cover plate, hinge, and stop means removed;

Fig. 5 is similar to that of Fig. 4 with a wall of the bellows section air chamber removed; and

Fig. 6 is a vertical section taken approximately on the line 6—6 of Fig. 1.

The same reference numerals throughout the several views indicate the same parts.

In the preferred embodiment of the invention, the hand bellows includes front and rear pivoted cover plates 17 and 19, respectively, and an accordian pleated or camera-type bellows section 21, disposed between and secured to the inside faces of the cover plates. Located above the lower edge of each of the cover plates 17 and 19 are a pair of laterally spaced openings 23, with the openings 23 in both plates being axially aligned with each other and with the openings 25 provided through the lower folds of the bellows section 21. A flexible hinge strip 27, preferably a leather thong, extends along the outer face of the rear cover plate 19 and is reeved through the aligned openings 23 and 25 with its ends being knotted at 29 in a manner so as to maintain the lower portion of the bellows section 21 in compressed position.

Extending upwardly from each of the top edges of the cover plates 17 and 19 is an integrally formed handle 31 provided with a hook or nail receiving opening 33 to facilitate storage of the bellows. The cover plates 17 and 19 are provided with aligned apertures 35 which are disposed above the top of the bellows section, see

2

Fig. 6, and through which is passed a flexible strip 37, preferably a leather thong, having on one of its ends a knot 39 which bears against the outer face of the front cover plate 17 while its other end is knotted at 41 to an intermediate portion of the strip to form a loop. As seen from Figs. 3 and 6, the distance between the flexible strip knots 39 and 41 is equal to the desired degree of expansion of the bellows section 21 and thus as the cover plates 17 and 19 are moved away from each other, the knots 39 and 41 engage the outer faces of the plates thereby to limit their movement. The looped portion of the flexible strip 37 is adapted to be disposed over the cover plate handles 31, as shown in Fig. 2, to maintain the bellows in closed or compressed position. Alternatively, the flexible strip loop may also be employed for hanging the bellows from a nail or hook for storage.

While any material having sufficient rigidity may be employed in fabricating the bellows cover plates 17 and 19, a thermosetting plastic material, such as polystyrene, appears to be most satisfactory from the standpoint of economy, appearance, and ease of manufacture, although the invention is not limited to a bellows formed of any particular material. As seen from Fig. 1, the outer faces of the cover plates 17 and 19 have a substantial free area upon which the manufacturer may place his name or mark or a decorative design.

With reference to Figs. 4—6, the bellows section 21 has approximately the same peripheral outline or configuration as that of the cover plates 17 and 19 and is formed of a flexible sheet material, such as paper, which is pleated by sharp fold lines in a manner similar to that employed in the construction of a conventional camera bellows. To insure that the bellows section bends only at its fold lines when it is collapsed or compressed, the bellows section walls adjacent to the fold lines are stiffened or reinforced by means of a reticulated sheet, such as paper, which is adhesively secured to the inside wall of the bellows during its manufacture as shown, for example, in the patent to J. A. Noble, 1,908,531. At each end of the bellows section 21 is a wall 43 of sheet material such as cardboard which has its marginal edges engaged between or embraced by the last or endmost internal slot or groove of the pleats or folds of the bellows, and if desired may be secured thereto as by staples 45. The walls 43 and the bellows section 21 form an air chamber into which air is drawn and from which air is expelled during expansion and contraction of the bellows section 21 by the movement of the cover plates 17 and 19.

To facilitate the drawing and expelling of air into and from the air chamber, the walls 43 are provided with openings 47 near their lower ends and the inside faces of the cover plates 17 and 19 each have a groove 49 which extends from their lower edges to and adjacent the openings 47 in the air chamber walls. To insure that the bellows section 21 will be expanded as the cover plates 17 and 19 are moved away from each other and to prevent any leakage of air from between the bellows section and the cover plates, the ends of the bellows section are secured to the inside faces of the cover plates by an adhesive. Thus, as the plates 17 and 19 are moved away from each other, air is drawn through the cover plate grooves 49 and wall openings 47 into the air chamber, with the air taking the reverse path as it is expelled. Since the air can leave the air chamber only through the cover plate grooves 49, the air will be expelled in two streams, one from each groove 49, which meet or intersect below the lower edge of the hand bellows. It will be noted that since the grooves 49 are inclined relative to each other, the air streams from the grooves 49 will meet or intersect at different points as the cover plates are moved towards each other since the angle between

the grooves 49 is reduced by such movement. In other words, the point at which the air streams from the grooves 49 intersect will shift in a direction away from the lower end of the bellows as the cover plates are moved to compress the bellows section 21.

To automatically expand the bellows section 21, a coiled compression spring 51 is fixed within the air chamber near the upper end thereof and urges the cover plates away from each other. As seen from Figs. 5 and 6, the inside face of each air chamber wall 43 is provided with a retainer strip 53 of semi-flexible sheet material such as cardboard, for example, fixed to the wall 43 as by staples 55. The spring 51 is positioned by merely sliding one spiral loop or coil of the spring upwardly between each of the retainer strips 53 and the walls 43, as seen in Fig. 6. The expansive force of the spring, working against the inclined or diverging faces 43, will tend constantly to wedge the end convolutions of the spring firmly into the retaining pockets or slots formed between the parts 43 and 53.

Thus, with the bellows section 21 adhesively secured to the inside faces of the cover plates 17 and 19, and with the lower ends of the cover plates 17 and 19 drawn together by the flexible hinge strip 27 so as to dispose the lower portion of the bellows section in compressed relation, removal of the loop of the flexible strip 37 causes the upper portions of the cover plates to automatically move away from each other due to the outward force of the compression spring 51. As this movement of the cover plates takes place, air is drawn into the air chamber and it is therefore necessary for the user to only apply a bellows compressing force in the operation of the bellows.

It is seen from the foregoing disclosure that the above mentioned objects of the invention are well fulfilled. It is to be understood that the foregoing disclosure is given by way of illustrative example only, rather than by way of limitation, and that without departing from the invention, the details may be varied within the scope of the appended claims.

What is claimed is:

1. A pneumatic hand bellows including an accordian pleated bellows section, end walls having approximately the same peripheral outline as said bellows section disposed within the endmost pleats of said bellows section with their marginal edges being embraced thereby, said bellows section and end walls forming an air chamber, a cover plate disposed at each end of said bellows section and secured thereto, a flexible hinge strip extending through and pivotally connecting edge portions of said cover plates and the bellows section pleats adjacent thereto with said pleats maintained in compressed relation, openings in said end walls, grooves on the inside faces of said cover plates extending from said end wall openings to an edge thereof, said grooves providing a plurality of air channels through which air is drawn into and expelled from said air chamber as said bellows section is expanded and compressed, a spring member positioned within said air chamber urging the portions of said cover plates opposite said pivotally connected edge portions away from each other to automatically expand said bellows section, and flexible stop means extending through said cover plates to limit the movement of said cover plates away from each other as the spring member automatically expands the bellows section.

2. A pneumatic hand bellows including an accordian pleated bellows section, end walls having approximately the same peripheral outline as said bellows section disposed within the endmost pleats of said bellows section with their marginal edges being embraced thereby, said bellows section and end walls forming an air chamber, a cover plate disposed at each end of said bellows section and secured thereto, a flexible hinge strip extending through and pivotally connecting edge portions of said cover plates and the bellows section pleats adjacent thereto with said pleats maintained in compressed relation, openings in said end walls, grooves on the inside faces of said cover plates extending from said end wall openings to an edge thereof, said grooves providing a plurality of air channels through which air is drawn into and expelled from said air chamber as said bellows section is expanded and compressed, a spring member positioned within said air chamber urging the portions of said cover plates opposite said pivotally connected edge portions away from each other to automatically expand said bellows section, and flexible stop means extending through said cover plates to limit the movement of said cover plates away from each other as the spring member automatically expands the bellows section.

to with said pleats maintained in compressed relation, openings in said end walls, and grooves on the inside faces of said cover plates extending from said end wall openings to an edge thereof, said grooves providing a plurality of air channels through which air is drawn into and expelled from said air chamber as said bellows section is expanded and compressed.

3. A pneumatic bellows including a pair of cover plates having handle means extending from one end thereof, an accordian pleated bellows section disposed between and secured to said cover plates to form an air chamber, said cover plates being recessed to form a plurality of discharge openings extending from the ends of said bellows section to the edges of said cover plates, said discharge openings being separated from each other by an edge portion of said bellows section and serving to direct air streams from said air chamber to the exterior of said bellows so that said air streams intersect outwardly of the bellows at various angles as said bellows section is compressed.

4. A pneumatic hand bellows including a bellows section, end walls cooperating with said bellows section and with said bellows section forming an air chamber, a cover plate disposed at each end of said bellows section and secured thereto, hinge means connecting edge portions of said cover plates and bellows section pleats adjacent thereto with said pleats in compressed relation, and means extending from said air chamber to the exterior of said hand bellows for drawing air into and expelling air from said air chamber as said bellows section is expanded and compressed, said means for drawing air into and expelling air from said chamber including grooves formed in the respective inner faces of said cover plates, the groove in one plate lying approximately opposite the groove in the other plate.

5. Pneumatic hand bellows including an accordian pleated bellows section capable of endwise expansion and contraction, a pair of rigid end plates secured to and covering the ends of said bellows section, a coil compression spring within said bellows section exerting outward force on said end plates to tend to separate them from each other, a flexible thong passing through both end plates adjacent one side of said bellows section and maintaining said end plates relatively close to each other at said side of said bellows section with said side relatively tightly compressed between the end plates while the opposite side of said bellows section may be expanded and contracted in use, and an air discharge passageway formed as a groove on the inner face of one of said end plates, one part of said groove communicating with the space within said bellows section, said groove extending thence past said tightly compressed side of said bellows section to an open end at an edge of said one of said end plates.

6. Pneumatic hand bellows including an accordian pleated bellows section capable of endwise expansion and contraction, a pair of rigid end plates secured to and covering the ends of said bellows section, hinge means holding said end plates relatively close to each other at one side of said bellows section with the pleats of said section relatively tightly compressed between said plates at said side while the two plates may swing relative to each other on said hinge means, each plate having air discharge passage means in fixed relation to such plate for discharging a stream of air outwardly past the edge of the plate approximately at said hinge means and approximately in a continuation of the plane of the plate, the air discharge passage means of one plate being alined with the air discharge passage means of the other plate substantially in a common plane perpendicular to both plates so that the streams of air discharged from the two passage means upon compression of said bellows section will intersect each other at a variable distance forwardly from the hinge side of the bellows.
